UNITED STATES PATENT OFFICE.

LOUIS J. MONAHAN, OF OSHKOSH, WISCONSIN.

CONTROLLER.

No. 859,186.

Specification of Letters Patent.

Patented July 2, 1907.

Application filed July 11, 1906. Serial No. 325,737.

To all whom it may concern:

Be it known that I, LOUIS J. MONAHAN, a citizen of the United States, residing at Oshkosh, in the county of Winnebago and State of Wisconsin, have invented 5 new and useful Improvements in Controllers for Explosive-Engines, of which the following is a specification.

The invention relates to a new controller or speed changing and reversing device for explosive engines, 10 especially of the marine type.

The object of the invention is to provide a simple and reliable controller whereby the speed of the engine can be changed instantly and the engine can be reversed while running.

15 A further object is to so arrange the parts so they will be convenient and within easy reach of the operator.

In the drawings Figure 1 represents an engine with the complete device attached. Fig. 2, shows the controller complete detached. Fig. 3, shows a detail of 20 the brush or insulated electrode. Figs. 4 and 5, show two views of the revolving contact collar.

In the drawings, the numeral 1 represents an internal combustion engine of the marine type; 2, is a side plate bolted onto the crank case; 3, an extending end 25 of the crank shaft; and 4, a fly wheel. The side plate 2 is turned down a short distance from the end and a bracket casting, 5, of approximately the form shown, is bored out and sleeved over the turned part on the side plate 2. The bracket is split through the lower 30 side and has the lugs, 6, cast solid therewith and a cap screw is tapped into one of the said lugs and fits loosely through the other so that by tightening the said screw, the bracket will be clamped tightly to the side plate. The bracket, 5, is of peculiar form. The extending 35 post, 7, is for the purpose of limiting the throw of the lever about the axis of the bracket by striking webs 8, placed on the side plate for the purpose. The upper part of the bracket extends backward in order to extend away from the fly wheel. A lever, 9, preferably 40 of steel or brass, is fitted into a groove (the latter being cast in the upper portion of the bracket 5, and held securely therein by means of a tap bolt, 10, passing through the bracket and lever. At the upper end of the lever a switch is provided, comprising a brass clip, 45 11, of approximately the form shown and fulcrumed at 12 to a cap screw or otherwise. A brass round head machine screw, 13, is arranged to extend through the lever and insulated therefrom by means of fiber tubes and washers and held therein by means of nuts, 14, at 50 the rear of the lever. The point of the clip, 11, is arranged to rest in the slot of the screw head, 13, and normally held therein by means of a spring, 15.

A contact collar is shown in Figs. 4 and 5 and is composed of a flanged ring, 16, with a segment, 17, 55 extending across the width of the contact collar and forming part thereof. A fiber washer, 18, is cut to

a form to slip over the brass hub of the ring and around the segment. This fiber is held to the brass ring by means of rivets, 19, passing through the fiber and brass. After they are riveted together, the outside 60 of the contact collar is turned leaving the brass segment and fiber even on the periphery. A round lug, 20, is cast with the brass ring, as shown, and is adapted to fit into a hole in the fly wheel hub so that it will be driven by and revolve with the fly wheel. 65 A brass block, 21, is secured to the bracket by means of two machine screws, 22. The block 21 is insulated electrically from the bracket by means of a flat piece of fiber, 23, and by tubes and washers of fiber around the screws, 22. The block has a groove cut 70 therein its whole length, as shown in Fig. 3, and a brass block or brush 24, is fitted loosely therein and has a hole drilled downward from its top to take a spring 25. A flat strip, 26, is secured to the top of the block by means of two screws, as shown, and covers 75 the groove in the said block and also serves to hold the spring down into the hole in the brush, 24. This flat strip, 26, extends a short distance past the block, 21, and has a screw or binding post fitted at the end for the purpose of attaching a wire to conduct a current 80 of electricity thereto. The fiber strip, 23, serves to cover the groove in the block when secured to the bracket so that the brush, 24, has up and down movement only and is held down by means of the spring 25.

In operation, a wire from the spark coil or battery 85 is attached to the screw or binding post on the flat strip, 26, and the remaining wire to the screw, 13, at the rear or under the nuts, 14. It will be seen that the circuit is closed between the lever and the contact, 13, and that when the segment of the contact 90 collar, 17, comes in contact with the brush, 24, the circuit is also closed between the bracket and insulated block, 21, but when the contact collar revolves still further, it breaks the circuit as the brush rides on the fiber portion of the contact collar and is thereby insulated electrically. It is also obvious that by moving the lever to the right or left, the time of contact between the contact collar and brush is changed with relation to the cam or crank shaft, that is, the time of ignition is advanced or delayed, according to the position of the lever and bracket. 95

The device is principally adapted to two cycle engines which are capable of running in either direction. To reverse the engine, the lever is moved over to the extreme end of its travel, opposite to the direction the 105 engine is running in and at the same time, the switch, 11, is pressed thereby, disconnecting the current so the engine will slow down; just before the engine stops, the switch is released and the current again connected, starting ignition, and on account of the 110 extreme early ignition at slow engine speed, the piston starts downward before it reaches the upward

center, thus running in the opposite direction. The engine can be reversed back again by moving the lever to the other extreme end of its travel and using the switch as before stated. The screw, 6, is only used to keep a reasonable tension on the bracket so it will stay where set.

Having fully described my invention what I claim and desire to secure by Letters Patent is:—

1. In a controller or timer for explosive engines the combination with an engine having a side plate (2), of a bracket of suitable form having the extending lug 7 sleeved over the side plate and adapted to have a limited travel about the said side plate, an upward extending lever or handle attached to the said bracket and having an electric switch mounted on its upper end, a grooved block secured to and insulated from the said bracket, a brush fitted loosely to a groove in the said grooved block, the said brush having a hole drilled lengthwise therein but closed at one end, a spring contained in the said hole, means for holding the spring therein, a contact collar comprising a ring with a brass segment on its periphery adapted to be sleeved on the crank shaft and revolve under and in contact with the said brush under the tension of the said spring, and webs (8) forming part of the said
2. In a controller for explosive engines, the combination with a bracket of suitable form and having an upward extending lever or handle, of a switch mounted near the end of the said lever comprising a clip, 11, fulcrumed to the said lever, an insulated contact, 13, passing through the lever, a suitably formed block, 21, secured to and insulated from the said bracket and having a groove its entire length; a brush, 24, fitted loosely in the said groove and having a hole therein, a spring arranged in the said hole, 35 a flat strip, 26, secured to the top of the said block, 21, and against the said spring and having an extending portion to form a contact, and a contact collar adapted to revolve beneath and in contact with the said brush.
3. In a controller an electrical contact collar comprising 40 a brass flanged ring, 16, with a segmental projection 17, and having an extending lug, 20, a fiber washer 18, secured to the brass ring and having its periphery continuous with the said segment, 17, for the purpose set forth.

In testimony whereof I affix my signature, in presence 45 of two subscribing witnesses.

LOUIS J. MONAHAN.
